US00D669865S

(12) **United States Design Patent**
Gilbert et al.

(10) **Patent No.:** US D669,865 S
(45) **Date of Patent:** ** Oct. 30, 2012

(54) **CONTROL PANEL**

(75) Inventors: **Christopher Jon Gilbert**, Moreland Hills, OH (US); **Judy Riley**, Valley City, OH (US); **Johan Liden**, New York, NY (US); **Yifei Zha**, Astoria, NY (US); **Jinmu David Staddon**, Brooklyn, NY (US)

(73) Assignee: **Moen Incorporated**, North Olmsted, OH (US)

(**) Term: **14 Years**

(21) Appl. No.: **29/389,084**

(22) Filed: **Apr. 6, 2011**

(51) **LOC (9) Cl.** 13-03

(52) **U.S. Cl.** **D13/162**; D10/49; D23/249

(58) **Field of Classification Search** D13/162, D13/164, 177; D10/49, 50, 96; D23/249, D23/254, 304; 4/559, 597, 675-678; 16/110.1, 16/441; 137/360, 801; 200/333, 336, 341; 236/12.1, 12.11, 12.12; 251/129.01; 700/17

(57) **CLAIM**

The ornamental design for a control panel, as shown and described.

DESCRIPTION

FIG. 1 is a perspective view of a first embodiment of a control panel of the new design;

FIG. 2 is a front elevational view of the control panel of FIG. 1;

FIG. 3 is a left side elevational view of the control panel of FIG. 1, the right side elevational view being a mirror image thereof;

FIG. 4 is a top plan view of the control panel of FIG. 1;

FIG. 5 is a perspective view of a second embodiment of a control panel of the new design; and,

FIG. 6 is a front elevational view of the control panel of FIG. 5, the top plan view being the same as the top plan view of FIG. 4.

The portions of the Figures shown in broken lines are not part of the claimed design and are for illustration only.

1 Claim, 4 Drawing Sheets
